(57) **CLAIM**

The ornamental design for a wall mount as shown and described.

DESCRIPTION

FIG. 1 is a bottom front left perspective view of the wall mount;

FIG. 2 is a front plan view of the wall mount shown in FIG. 1;

FIG. 3 is a left side plan view of the wall mount shown in FIG. 1, the right plan view being a mirror image thereof; FIG. 4 is a rear plan view of the wall mount shown in FIG. 1;

FIG. 5 is a top plan view of the wall mount shown in FIG. 1;

FIG. 6 is a bottom plan view of the wall mount shown in FIG. 1;

FIG. 7 is a right rear perspective view of the wall mount shown in FIG. 1; and,

FIG. 8 is a top front right perspective view of the wall mount.

The broken line showing of the monitor in FIGS. 1–8 depicts environment and forms no part of the claimed design.

1 Claim, 8 Drawing Sheets
